CORD PROCESSING APPARATUS

Raymond E. Solliday and Herbert E. Riggs,
Akron, Ohio, assignors to Wingfoot Corpora-
tion, Akron, Ohio, a corporation of Delaware

Application May 4, 1946, Serial No. 667,332

8 Claims. (Cl. 57—35)

1

The present invention relates to an improved form of thread processing apparatus. More particularly, the invention pertains to a novel means for use in the manufacture of doubled and twisted thread, yarn, cord, and the like, hereinafter referred to generally as "cord."

One of the important objects of the present invention is to provide an improved form of device which is adapted to be applied to conventional doubler-twister apparatus for introducing a definite predetermined tension on the composite cord formed by the doubling and twisting operation in the course of which a plurality of individual threads of natural or synthetic origin are joined to form a cord and then twisted together.

It is a further object of the present invention to provide a mechanism which will enable the production of an improved cord characterized by a more uniform twist and gauge.

It is a still further object of the present invention to provide an apparatus which is capable of manufacturing a finished cord on which all of the loose and projecting fibers of the several component threads are laid in substantially parallel alignment, thereby producing a composite cord having a smooth finish.

It is another and still further object of the present invention to afford a means capable of operable association with a conventional doubler-twister apparatus which will apply heat for the drying and burnishing of a chemically treated compositized cord.

Other objects and advantages of the present invention will become apparent as the following detailed description of one form of installation illustrated in the accompanying drawings and embodying the principles of the present invention proceeds.

The device of the invention is particularly advantageously adapted to be employed in combination with conventional forms of doubling and twisting apparatus. Such apparatus is capable of handling a large number of individual thread supply packages, each of which supplies a single thread, and for joining with other similar threads from adjacent series of supply packages to form a composite cord. Conventional doubler-twister apparatus embodies a plurality of cord-forming units arranged in spaced generally parallel relation extending longitudinally of the machine as a whole.

Figure 1 represents a partial end elevation of a typical form of doubler-twister apparatus with which the teachings of the present invention are particularly advantageously adapted to be em-

2

ployed. Figure 2 is an enlarged front elevation of the apparatus of the invention with parts broken away. Figure 3 is an elevation of the apparatus of Figure 2 as seen from the line 3—3 therein. Figure 4 is a sectional view taken along the line 4—4 in Figure 2. Figure 5 represents a fragmentary front elevation of the apparatus of the invention corresponding generally to Figure 2.

10 In Figure 1 of the drawings, the reference numeral 1 designates generally a doubler-twister apparatus to which the cord processing device of the invention has been applied. The doubler-twister apparatus 1 is provided with a frame 2 on which 15 is mounted a spindle support 3 which carries a plurality of spindles 4 and guides 5 disposed in spaced, parallel relation in a substantially horizontal plane.

Each of the spindles 4 carries a supply spool 20 6 for providing a thread end 7 to be incorporated into a composite cord in the course of the operation of the doubler-twister apparatus. The several threads 7 pass from the supply spools 6 through a gathering guide 8 which serves to arrange them in generally parallel relation to form the cord 9. The cord 9 next passes over and in contact with the surface of a dip roll 10 supported by a longitudinally extending freely rotatably mounted shaft 11. The dip roll 10 is disposed in 25 a supply of processing liquor contained in a trough 12 which is supported from the frame 2 by a supporting bracket 13.

30 After leaving the dip roll 10, the composite cord 9 is directed about the under side of a positively driven roll 14, around an idler roll 16, and under a second driven roll 15. This arrangement of the positively driven rolls 14 and 15 in combination with the idler roll 16 insures a positive, uniform feed of the cord to the subsequent twisting operation. The cord 9 next passes over a driven 35 burnishing roll 17, the function of which will be explained in greater detail hereinafter, to a guide eye 18 which directs the cord to a traveler 19 mounted upon a ring 20 on the ring rail 21 and finally to the collecting spool 22.

40 The build-up of the package of cord 9 on the collecting spool 22 is achieved in a conventional manner by the reciprocation of the ring rail 21 in combination with the action of the traveler 19 as 45 it traverses a circular path about the ring 20. The collecting spool 22 is simultaneously driven at a high speed of rotation by a pulley 23 which is actuated by a belt or dip drive 24. The collecting spool 22 is disengageably attached to the pulley 23 50 which is in turn mounted upon a stub shaft 25

disposed in a bearing support 26. The fixed rail 27 carries a plurality of the stub shafts 28 and bearing supports 26 disposed in spaced relation along the longitudinal dimension of the machine. The fixed rail 27 is supported from the frame 2 5 of the machine as by means of a frame mounting bracket 28.

The cord processing apparatus of the present invention, as more clearly illustrated in Figures 2 to 4, inclusive, of the drawings, serves to provide a compressing and burnishing effect upon the cord 9 as it passes over the burnishing roll 17 in 10 its path of travel from the driven rolls 14 and 15 of the twister feed mechanism to the collecting spool 22. The shafts 29 and 30, upon which are mounted the driven rolls 14 and 15, respectively, are supported at one end thereof by a suitable bearing bracket 31 mounted upon the frame 2 15 of the doubler-twister apparatus 1 and at the other end thereof in bearings 32 on an end plate 33 forming part of the frame 2.

The ends of the shafts 29 and 30 extend slightly beyond the end plate 33, thereby enabling the shaft 29 to carry a sprocket 34 and chain 35 of a driving mechanism which is actuated by the prime mover (not shown) of the doubler-twister apparatus 1. A spur gear 36, secured to the shaft 29, transmits power to a spur gear 37 mounted upon the end of the shaft 30 through an idler gear 38 25 freely rotatably mounted upon a stud 39 secured to the end plate 33.

A suitable housing 40 may be employed to enclose all of the driving apparatus at the one end of the doubler-twister apparatus 1 and disposed beyond the end plate 33 of the frame 2 thereof. It will be understood that by virtue of the gearing relation embodying the several gears 36, 37, and 38, the driven rolls 14 and 15 comprising the twister feed mechanism be rotated in the same direction. The driven rolls 14 and 15 will insure a positive feed of the cord 9 to the twisting apparatus and the collecting spool 22 disposed therebelow. The idler roll 16 associated with the driven rolls 14 and 15 is advantageously weighted to insure constant frictional engagement between the cord 9 and the driven rolls 14 and 15 in the operation of the apparatus.

The burnishing roll 17 is supported by a shaft 41 mounted in a bearing bracket 42 on the frame 2 at one end thereof, and a boss 43 in the end plate 33 at the other. A pair of spaced brackets 44 are arranged to adjustably support the weighted idler roll 16 to enable it to be raised and lowered with respect to the driven rolls 14 and 15 to facilitate the threading up of the apparatus. A single idler roll 16 is provided for each individual cord 9 at each position on the machine extending from end to end thereof.

A portion of the shaft 29 extending through the bearing bracket 31 rotatably supporting the driven rolls 14 and 15 carries a single pulley 45. A dual idler pulley 46 embodies a pair of pulley segments 47 and 48 of different diameters and is rotatably supported by bearing bracket 49. The drive for pulley 46 is achieved by means of a belt 50 which is trained over the pulley 45 and pulley segment 47.

The pulley 46 in turn drives a smaller single pulley 51 by means of belt 52 which contacts the larger of the pulley segments 48. The pulley 51 is mounted upon the end of the shaft 41 supporting and driving the burnishing roll 17. By virtue of the pulley sizes employed in transmitting the drive from the shaft 29 to the shaft 41, the burnishing roll 17 is driven at a speed

somewhat higher than the rate of delivery of the cord from the twister feed mechanism embodying the several driven rolls 14, 15 and idler roll 16.

It will be readily understood that any desired conventional form of drive can be substituted for that shown and described. Moreover, any desired driving relationship can be achieved by changing pulley sizes, gearing, and the like. It is contemplated by the present invention to rotate the burnishing roll 17 at a speed such that it will exert a slight tension upon the cord 9 being delivered from the twister feed mechanism embodying the rolls 14, 15 and 16, thereby permitting a slight slippage of the cord 9 with respect to the surface of the burnishing roll 17.

The slipping action of the cord 9 on the roll 17 causes the cord to roll upon itself and, thus, to progress in a direction axially of the roll, thereby enabling the projecting fibers comprising the individual threads in the cord to be closely compressed into the body of the cord as it is subsequently twisted. To prevent excessive axial progression of the cord, a restraining collar 53 is positioned on the outer periphery of the burnishing roll 16 adjacent the path of contact of the cord upon the surface of the roll and defining a more or less restricted area over which the cord may move along the roll.

The use of the collars 53, one for each cord 9, on the burnishing roll 17 serves to increase the effective surface of contact with the traveling cord 9. It will be understood that when the cord 9 is disposed in contact with one face of the collar 53, as well as the roll 17, the burnishing action thereon is produced both by the edge of the collar and by the portion of the roll surface adjacent thereto.

If desired, heat may be supplied to the burnishing roll 17 to facilitate the smoothing and drying effect upon the cord 9. This heating step may be accomplished in any one of several different ways of which the method illustrated in Figure 5 of the drawings is but one. In the illustrated modification of the invention, a burnishing roll 54 is provided with a perforated hollow shaft 55 for introducing steam from a suitable supply source 56 to the interior of the roll. The steam supply 56 is connected to the shaft 55 as by means of piping 57 and coupling 58. Thus, the roll 54 may readily be uniformly heated to any desired temperature to effectively dry and burnish the cord 9.

Other modifications may be made in the apparatus of the invention without in any way departing from the spirit or scope of the invention. It has already been suggested that the pulley drive for the burnishing roll might advantageously be supplanted by a gear drive unit. Moreover, any form of heating of the housing is satisfactory.

While in accordance with the patent statutes one best known embodiment of the invention has been illustrated and described in detail, it is to be particularly understood that the invention is not limited thereto or thereby, but that the inventive scope is defined in the appended claims.

We claim:

1. In a thread processing apparatus embodying a plurality of thread supply packages, means joining the several threads, twisting means, and positively driven feeding means for delivering the joined threads to the twisting means at a substantially constant rate, rotatable burnishing means between the feeding means and the twist-

ing means for contact with the joined threads, means actuating the feeding means and the burnishing means and differential drive means associated with the actuating means to afford a rotational speed differential between the feeding means and the burnishing means.

2. In a thread processing apparatus embodying a plurality of thread supply packages, means joining the several threads, twisting means, and positively driven feeding means for delivering the joined threads to the twisting means at a substantially constant rate, rotatable burnishing means between the feeding means and the twisting means for contact with the joined threads, means actuating the burnishing means to afford a rotational speed differential with that of the feeding means, and means heating the burnishing means.

3. In a thread processing apparatus embodying a plurality of thread supply packages, means joining the several threads, twisting means, and positively driven feeding means for delivering the joined threads to the twisting means at a substantially constant rate, rotatable burnishing means between the feeding means and the twisting means for contact with the joined threads, means actuating the burnishing means to afford a rotational speed differential between the burnishing means and the feeding means, means between the joining means and the burnishing means subjecting the joined threads to processing treatment, and means heating the burnishing means.

4. In a thread processing apparatus embodying a plurality of thread supply packages, means joining the several threads, twisting means, and positively driven feeding means for delivering the joined threads to the twisting means at a substantially constant rate, rotatable burnishing means between the feeding means and the twisting means for contact with the joined threads, means actuating the burnishing means to afford a rotational speed differential between the burnishing means and the feeding means, means between the joining means and the burnishing means subjecting the joined threads to processing treatment, means heating the burnishing means, and means on the burnishing means restraining the joined threads from shifting axially along the burnishing means.

5. In a doubling and twisting apparatus having plurality of positions, each of which embodies a number of supply packages of thread and the like, means joining the several threads, and a driven twisting means, rotatable means embodying a surface of revolution over which the doubled threads pass, means actuating said rotatable means at a predetermined rotational speed to afford a slipping contact with the thread as it passes from the supply packages to the twisting means, and annular means on the rotatable means for restraining the shifting of the thread axially of the surface of revolution.

6. In a doubling and twisting apparatus having a plurality of positions each of which embodies a number of supply packages of thread and the like, means joining the several threads, a positively driven feeding means, and a driven twisting means, rotatably mounted means having a

surface in contact with which the doubled threads are directed in passing from the supply to the twisting means, means actuating the rotatably mounted means at a predetermined rotational speed to afford a rotational speed differential between the feeding means and the rotatably mounted means, means heating the rotatably mounted means, and means on the surface of the rotatably mounted means for preventing excessive movement of the threads along the surface of the rotatably mounted means in a substantially axial direction.

7. In a thread processing apparatus including a plurality of thread supply packages each of which supplies an individual thread, means joining the several threads, a dip means applying a liquid processing treatment to the joined threads, a pair of feed rolls about which the joined treated threads are passed, a twister for collecting and twisting the joined treated threads, and drive means for actuating the feed rolls and the twister at a constant predetermined rate, burnishing apparatus comprising a rotatably mounted roll disposed between the feed rolls and the twister for surface contact with the joined treated threads as they pass therebetween, and means for driving the rotatably mounted roll at a predetermined speed to afford slippage of the thread in contact with the rotatably mounted roll.

8. In a thread processing apparatus including a plurality of thread supply packages each of which supplies an individual thread, means joining the several threads, a dip means applying a liquid processing treatment to the joined threads, a pair of feed rolls about which the joined threads are passed, a twister for collecting and twisting the joined threads, and drive means for actuating the feed rolls and the twister at a constant predetermined rate, burnishing apparatus comprising a rotatably mounted roll disposed between the feed rolls and the twister for surface contact with the joined threads as they pass therebetween, means for driving the rotatably mounted roll at a predetermined speed differing from that of the feed rolls to afford slippage of the joined threads thereon, a ring on the burnishing roll adjacent the path of contact of the joined threads therewith for restraining the axial shifting of said threads along said roll, and means heating the burnishing roll.
